Charles E. Jones, Chicago, and Robert H. Crowle,
Berwyn, Ill.

Application July 20, 1953, Serial No. 26,051

Term of patent 14 years

(Cl. D74—5)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for a Calendar Stand, of which the following is a specification, reference being had to the accompanying drawing, forming a part thereof.

In the drawing:

Fig. 1 is a front perspective view of a calendar stand showing our new design;

Fig. 2 is a rear elevation; and

Fig. 3 is an end elevation.

The essential features of our design reside in the portions shown in full lines.

We claim:

The ornamental design for a calendar stand, as shown and described.

CHARLES E. JONES.
ROBERT H. CROWLE.
